JOHN GOTT, OF HOVE, BRIGHTON, ENGLAND, ASSIGNOR TO COMMERCIAL CABLE COMPANY, OF NEW YORK, N. Y., A CORPORATION OF NEW YORK.

WORKING SUBMARINE CABLES.

1,114,982.

Specification of Letters Patent.

Patented Oct. 27, 1914.

Original application filed March 18, 1912, Serial No. 684,572. Divided and this application filed July 31, 1912. Serial No. 712,509.

To all whom it may concern:

Be it known that I, JOHN GOTT, a subject of the King of Great Britain, and resident of Hove, Brighton, England, have invented 5 certain new and useful Improvements in Working Submarine Cables, of which the following is a specification.

In the drawing Figure 1 is a diagrammatic view showing the invention applied to 10 a duplex cable system; Fig. 2 a detail view of a simple relaying means; and Fig. 3 a detail diagrammatic view of the receiving apparatus.

This application is a division of my co- 15 pending application filed March 18, 1912, Serial No. 684,572, said application covering improvements in working submarine cables.

This invention relates to a system intended 20 to apply the international Morse code to the transmission of messages over long submarine cables, in place of the code now used whereby uniformity of working with land lines and other connections is established.

25 The invention primarily involves a method of transmission of the Morse code which enables it to be applied in the most economical manner as regards time.

It is well known that reversed currents 30 sent rapidly through a long submarine cable are the most effective in definition as received at the distant end of the cable—each following current having the effect of neutralizing the preceding one. In this invention every unit of each letter is formed by a reversed current so that in no case during transmission does an impulse of current of one polarity follow one of the same polarity. At the receiving end of the cable 35

40 these reversed currents form units of letters and are transformed in a simple manner, so that the signals come out in Morse characters, as if received through a short land line and are therefore easy to read and trans- 45

cribe. To obtain the reversals of polarity of the current to the line for each unit of a letter or signal with absolute uniformity and certainty, I make use of a transformer provided with primary and secondary coils, the 50 primary being placed in the earth circuit of a split, or double battery. Currents are induced in the secondary which is connected to and actuates a polarized relay. The induced currents in the secondary coil are reversed

according to the polarity of the last current sent into the cable and these reversals take place in regular sequence assuring that no two successive currents of the same polarity are sent into the line. One advantage of this method is that on making contact with the 55 key to charge the cable the battery contact in the relay is reinforced at the moment the key is depressed thus assuring perfect transmission. This is brought about by the action of the secondary coil. The sending of 60 messages through the cable is effected by the working of a single Morse key of the usual type so that the operator's mode of manipulation is exactly the same as if he were sending into any ordinary line, that is to say, to 65 transmit a dash impulse or signal the key is held down or closed longer than when transmitting a dot impulse or signal. Where it is desired to send messages automatically the 70 message is prepared on a perforated slip and the Wheatstone transmitter takes the place of the key; the reversing polarized relay being connected in circuit as for hand keying with the ordinary and well-known Wheat- 75 stone transmitter. The two upper contacts 80 of the vibrating contact arm are used to take the place of the key. So also where the system is applied for translation from a land line or short connecting cable, the usual receiving relay is connected to the reversing 85 polarized relay in the manner described for the hand key and the received Morse signals are translated in the cable into the form of my "reversed current alphabet" or alternating current alphabet. Also the relay re- 90 ferred to may work a sounder relay in a local circuit which, being connected in place of the single Morse key translates the signals from the short connecting lines or cables into the main cable. 95

Having described the method of transmission it remains to point out how the Morse code which is sent through the cable in the form of reversals for each unit of a letter, is retransformed into the common Morse code. 100

In all systems of relay repeaters on long cables hitherto used, the contact arm when at rest occupies a neutral position (known as no man's land) between two contact plates which are connected to the local battery in- 105 tended to actuate local instruments for repeating the signals either into another cable or to record the received signals. If we con-

nect the two contact plates together it follows that the movable contact-making tongue will record signals made on either side, and these signals will appear on the local apparatus as if made continuously on one contact. For example, two reversals will appear as four dots, (the letter "h" in Morse) and we shall have all the reversed signals received through the cable transformed into the well known Morse characters. These may be read by sound or printed on a Morse slip and similarly they may be repeated automatically to another distant station in the Morse characters. It follows from these observations that the cable relay, with its contact tongue and neutral center, will faithfully transmit the reversed Morse code into another cable in the form received, and that the final transformation takes place at the terminal station of the main cables where the message is either transcribed for delivery, or repeated inland.

In order that this invention may be clearly understood and properly carried into effect 25 it will now be described with reference to the accompanying drawings.

The invention consists mainly of a new disposition of parts to permit of the use of a code of signals consisting of reversed or 30 alternating currents for the successive units of a letter.

In the diagram Fig. 1, *a* designates a cable; *b* the artificial cables used for duplex working; *c*, *c'* the sending condensers; *e* the 35 wire connecting the key *d* to the apex of the bridge arms; *f* the front contact of the key; and *g* the back contact thereof. The front contact *f* is connected to a polarized relay *h*² by wire *j*; and the back contact is 40 connected to earth at *g'* and the discharge from the cable and condensers is directed to earth through said contact when the key is open. When the key is depressed the battery is connected to the cable, and when the 45 key is open and in engagement with the back contact the cable discharges to earth as described. To the two stops *h'* *h'* of the relay *h*² are connected the opposite poles of a split battery *l* *l'*, the center part of said battery being connected to earth through the 50 primary coil *P* of a transformer, the secondary coil *S* thereof being connected to the relay coils. The front contact *f* of the key is electrically connected to the movable 55 tongue or vibrating arm *h''* of the polarized relay. This tongue *h''* is adapted, as is usual, to make contact with either of the stops *h'* *h'*. When the key *d* is depressed the battery *l* or *l'* is connected to the cable 60 through the wires *j* and *e*, and a current will be induced in the secondary coil *S* of the transformer, which current will firmly hold the tongue of the polarized relay against the stop with which it is in contact.

When the key is opened a reversal of cur-

rent in the secondary coil will take place and the vibrating tongue or arm will then be thrown against the other stop of the polarized relay, thereby reversing the polarity of the current to the front stop *f* 70 of the key and consequently to the line when the key is again depressed or closed. It is manifest that the same cycle of operations follows each depression and raising of the sending key. The result of this is that the 75 current impulse sent to the line at each key operation will be opposite in polarity to the previously sent current impulse. It is, therefore, clear that in operating the key for sending Morse code signals each signal unit 80 impulse, whether it be a dot or a dash, will be opposite in polarity to the preceding signal unit impulse and, therefore, no two succeeding signal unit impulses will be of the same polarity.

Fig. 2 simply illustrates how the tongue *T* of a relay connected to a land line, or short cable takes the place of the key of Fig. 1. It also illustrates how the rocking contact bar of a Wheatstone transmitter is connected 90 in place of the key to send automatically into the cable, the upper two contacts of the transmitter only being used.

Fig. 3 represents the apparatus used at the receiving or terminal end of the cable. 95 The two metal plates *v* and *v'* are separated by an insulator *y*. The contact making tongue *V* is actuated by an attachment to the signal coil of a recorder which coil is in circuit with the cable. Arriving signals 100 move this tongue from zero to *v* or *v'* according to the polarity of the arriving current. For the purpose of this invention the two metal plates are connected together by the wires at *W* and are in circuit with the local battery, etc. The instrument at *Z* may be a Morse recording instrument, a sounder or relay or other instrument. It will be clearly seen that rapid reversals will 105 be indicated by the sounder, for example, as dots or dashes, as if made on one contact only, as in ordinary Morse working.

I desire it understood that I consider any means for transmitting impulses of current to the line the equivalent of the transmitting key, and that where I use the term key it is, of course, to be understood that I include any equivalent device or apparatus. In re-laying from one cable into another, of course, the relay armature becomes a transmitting 115 key, likewise in any arrangement of apparatus in which the impulses of current are sent automatically, the automatic transmitting means becomes the key.

The receiving apparatus of Fig. 3 is 125 shown in connection with the transmitting apparatus of Fig. 1. It is manifest that the received signal impulses of current of alternating polarity are reproduced in the local circuit controlled by the receiving relay,

(and in which local circuit the coils of the receiving instrument or of the relay are arranged), as impulses of like polarity, precisely as the signals are produced in an ordinary telegraph system with a Morse key.

What I claim is:

1. A system of cable working comprising a cable, a sending key, a polarized relay, a transformer, and means whereby upon the

10 opening of the key the relay will be operated by the induced current in the transformer to reverse the connections of the battery to the line.

2. A system of cable working comprising a cable, a sending key for transmitting signal impulses of current, a polarized relay, a transformer, means whereby upon the opening of the key the relay will be operated by the induced current in the transformer to

15 change the polarity of the current to the line, and means at the receiving or terminal end of the line for receiving said signal impulses irrespective of their polarity.

3. A system of cable working comprising a cable, a sending key, a polarized relay, a transformer, a split battery grounded through the primary coil of said transformer, the secondary coil thereof being connected to the relay, whereby upon the opening of

20 the key the connections of the battery to the line will be reversed.

4. A system of cable working comprising a cable, a sending key, a polarized relay, and means whereby when the key is closed the

25 relay tongue will be held against its contact to complete the circuit to the cable and when the key is opened said means will cause the relay to reverse the polarity of the current to the line for the next key operation.

40 5. A system of cable working comprising a cable, a sending key, a polarized relay, and means whereby the cable charging current will induce a current through the relay to hold the relay tongue against its contact

45 when the sending key is closed and when the key is opened said means will cause the relay to reverse the polarity of the current to the line for the next key operation.

6. A system of cable working comprising a cable, a sending key, a polarized relay, and means whereby the cable charging cur-

rent will induce a current through the relay to hold the relay tongue against its contact when the sending key is closed, said means serving to reverse the position of the relay 55 tongue when the key is opened and to thereby change the polarity of the current to the line for the next key operation.

7. A system of cable working comprising a cable, a transmitting means for sending signal impulses into the cable, a polarized relay, a transformer, means whereby upon the opening of the transmitting means the relay will be operated by the induced current in the transformer to change the polarity of 60 the current to the line, and means at the receiving or terminal end of the line or cable for receiving said signal impulses irrespective of their polarity.

8. A system of cable working comprising a cable, a polarized relay, a transformer, the secondary coil of said transformer being connected to the coils of the relay, a split battery connected to the primary coil of the transformer and to the stops for the relay 70 tongue, and transmitting means for sending signal impulses of current into the cable said transmitting means when closed electrically connecting the relay tongue to the cable.

9. The method of working cables consisting in transmitting signal impulses of current through a polarized relay, sending a locally induced current through the relay at each opening of the transmitting means and 85 reversing the polarity of the current to the line through each movement of the relay.

10. A system of cable working comprising a cable, a polarized relay, means for sending signal impulses of current through the said 90 relay to the cable, means for producing a locally induced current through the relay upon each opening of the transmitting means, and means for reversing the polarity 95 of the current to the cable upon each operation of the polarized relay.

In testimony whereof I hereunto affix my signature in the presence of two witnesses.
